SAFETY CLASP

Reinhard Guyot, Burbank, Calif.

Application July 1, 1955, Serial No. 519,551

4 Claims. (Cl. 24—250)

This invention relates to improvements in safety clasps or clips of the character set forth in Letters Patent No. 2,269,662 issued January 13, 1942 and has as its general object the provision of a clasp which is utilizable in gripping overlying layers of deformable sheet material, such as cloth, in such fashion as to securely hold such layers against accidental separation without penetration of the material; a particular object of the invention being to provide a clasp which is capable of fastening together the folds of diapers applied to infants so as to obviate the use of pins for such purpose, thereby eliminating the hazards incident thereto.

Another object is to provide a clasp of the type in which the portion of the sheet material to be fastened thereby is draped over a lug or protuberance on a lever-arm and extended through a proximate encompassing frame to thereby hold the material against disengagement from the clasp, wherein the lug and frame are so shaped as to securely grip the material engaged thereby and in such fashion as to prevent accidental relative slipping of the material and clasp.

Another object is to provide a clasp of the above character which can be easily and quickly manipulated in effecting both its application to the material to be engaged and its removal therefrom.

Another object is to provide a mode of construction of the clasp whereby it may be readily and economically formed and assembled.

Another object is to provide a clasp embodying a yoke for positioning astride the layers of fabric and the like to be fastened together and including a lever-arm pivotally mounted on the yoke for swinging movement relative thereto, in which the pivotal connection between the arm and yoke is effected by a snap-on operation thereby greatly facilitating the assemblage of the parts.

A further object is to provide a formation in the yoke element of the clasp whereby material of appropriate thickness to be engaged thereby may be readily inserted therein.

With the foregoing objects in view together with such other objects and advantages as may subsequently appear the invention resides in the parts and in the combination, construction and arrangement of parts hereinafter described and claimed, and as illustrated by way of example in the accompanying drawing in which:

Fig. 1 is a perspective view of the clasp as seen from the front and one side thereof:

Fig. 2 is a similar view of the clasp as seen from the back and one side thereof:

Fig. 3 is a plan view of a sheet metal blank from which the yoke element of the clasp is formed:

Fig. 4 is a perspective view of the formed yoke element:

Fig. 5 is a perspective view of the lever-arm showing it detached:

Fig. 6 is a perspective view of a slip-on plug utilized in pivotally connecting the lever-arm and yoke:

Fig. 7 is a view in enlarged vertical section of the

2

clasp showing it in its open sheet material receiving position:

Fig. 8 is a view similar to Fig. 7 showing the clasp in its material engaging position; and

Fig. 9 is an enlarged detail in section of a fragmentary portion of the clasp showing the manner of locking the lever-arm relative to the yoke element in its clasping position.

Referring to the drawing more specifically A indicates generally a yoke which is initially formed as a flat substantially rectangular blank B consisting preferably of thin sheet metal as shown in Fig. 3, which blank is bent intermediate its ends to form overlying spaced apart oppositely curved front and back leg members 10 and 11 united by a spring bow 12. The front leg member 10 is formed adjacent the bow 12 with a narrow transverse slot 14 between which and the outer end of the leg member 10 is formed a substantially rectangular aperture 15 corresponding in width to the length of the slot 14 and separated therefrom by a narrow integral pivot bar 16, the side margins of the aperture 15 being aligned with the ends of the slot 14. The outer end of the aperture 15 is bordered by a rail 17 constituting the outer end portion of the leg member 10 which rail is formed on its inner end portions with marginal projections *a—a* spaced apart by a medial open slot *b* which projections constitute keepers as will later appear.

The back leg member 11 is formed with a trapezoidal opening 18 bordered by parallel inner and outer margins *c* and *d* and by side members having upwardly and inwardly inclined margins *e* and *f*, which opening extends longitudinally of the leg member 11 from the bow 12 to near the outer end of the leg member and extends laterally to near the side edges of such leg member.

As here shown the back leg member 11 is shortened relative to the front leg member 10 with the opening 18 in the former upwardly offset relative to the aperture 15 in the latter.

Hingedly mounted on the pivot bar 16 and thus carried on the leg member 10 is a lever arm C which is designed to swing partly through the aperture 15, it embodies an elongated handle portion 19 of substantially rectangular outline with its side margins slidably conforming to the side margins of the aperture 15. The upper end of the lever arm C is formed with a rearwardly extending protuberance 20 the outer end of which normally projects into the opening 18 in the leg member 11 when the handle portion 19 is positioned in parallel relation to the leg member 10. When thus positioned the outer end of the handle portion overlies and abuts the outer end portion or rail 17 of the leg member 10 thus limiting inward swinging movement of the lever arm C on the yoke A.

A feature of the invention resides in the mode of mounting the lever arm C on the pivot bar 16, which is accomplished by forming the upper end of the handle portion 19 with an open ended transversely extending tube 21 having as lot 22 in the lower portion of the front wall thereof so as to divide the latter whereby the tube 21 may be positioned astride the pivot bar 16 by passing the bar edgewise through the slot 22.

The bore 23 of the tube 21 is elongated in the general direction of the length of the handle portion 19 and is contoured to provide a semi-cylindrical space adjacent the slot 22 forming an arcuate seat spaced beneath the pivot bar 16 for the reception of a cylindrical slip-on plug 24 which is mounted in place after engaging the tube 21 with the pivot bar 16 by forcing it lengthwise through the tube 21, the plug 24 having a diameter slightly exceeding the width of the slot 22 so that the wall portion of the tube 21 forming the upper margin of the slot 22 constituting an inturned resilient lip 25 must

necessarily be sprung outwardly to permit passage of the plug 24 through the tube. On the plug 24 being thrust through the tube the inwardly presented margin of the lip 25 will spring against the outer periphery of the plug 24 and will bear thereon forwardly of its longitudinal axis thereby securely holding the plug in place. Clearance space 26 is provided between the upper portion of the plug 24 and the lower margin of the pivot bar 16 as shown in Fig. 9 in order to permit limited longitudinal movement of the lever arm C relative to the pivot bar whereby the lower end of the lever arm may be moved in and out of locking engagement with the keepers a—a, the lower end of the lever arm C being formed with notches 27 adapted to snugly receive the keepers a—a when the lever arm is in its innermost position with its outer end portion abutting the end portion 17 of the leg member 10.

The outer face of the lower end portion of the lever-arm is formed with a series of fine ribs 28, or otherwise roughened to afford gripping engagement with the surface of a thumb or finger impressed thereagainst in imposing a longitudinal thrust on the lever-arm when disengaging it from the keepers a—a.

The protuberance 20 is designed to be thrust against overlying layers of fabric or other sheet material interposed between the leg members 10—11, and to shove the portion of the fabric abutted by the protuberance into the opening 18 in the leg member 11, the margins c, d, e and f of which opening then serve to drape the fabric over the outer end portion of the protuberance as will presently be described.

As a means for enhancing interengagement of the fabric and protuberance the latter is formed with upwardly and inwardly inclined opposite sides formed with a series of stepped or offset transverse ledges g paralleling the upper edges of the protuberance and having sharp angular ridges h terminating at their outer ends in upwardly presented sharp corners i.

The lever-arm C and the plug 24 are preferably formed of a synthetic resin or a plastic such as "Lucite," polystyrene and the like.

In the operation of the invention, the lever-arm C is swung outwardly and upwardly on the yoke A as shown in Fig. 7 so as to withdraw the protuberance 20 from between the leg members 10—11 whereupon overlying layers D of the material to be engaged by the clasp are positioned within the yoke A either by advancing the leg members 10—11 thereof astride the layers or by feeding the layers therebetween so as to position the layers over the opening 18 in the leg member 11 and in front of the upper end of the protuberance 20. The lever-arm C is then swung downward so as to advance the protuberance 20 against the material D and thrust the engaged portion of the material through the opening 18 as shown in Fig. 8, the material being confined by the margins c, d, e and f of the opening 18 thereby being deformed and draped over the protuberance 20 and engaged by the ridges h and corners i so as to effect such secure interconnection of the clasp and the material as to prevent separation thereof until the lever-arm is moved to its open position. By locking the lever-arm in its closed position, which is effected by engagement of the keepers a—a in the notches 27 as shown in Figs. 8 and 9, accidental disengagement of the clasp from the material is prevented. Release of the lever-arm is accomplished by shoving it upward to free the notches 27 from the keepers a—a which movement is afforded by provision of the clearance 26 beneath the pivot bar 16 and space provided in the slot 14 above the upper end of the lever-arm, this operation being effected by engaging the ribs 28 with a thumb or finger and exerting an upward thrust on the lever-arm.

By forming the yoke A with the spring bow 12 the leg members 10—11 are resiliently connected together and are thereby subject to being yieldably spread apart under tension, whereby a particular clasp is rendered adjustable

and adaptable within limits for use in clasping materials D of various thicknesses, it being contemplated however to provide the clasp in various sizes according to various requirements and applications thereof.

An important feature of the invention is the simplicity of construction of the parts of the clasp and in the mode of their assemblage whereby it may be economically produced, and which is attained by forming the yoke of sheet metal with the integral pivot bar 16 and forming the lever-arm of a plastic with the split tube 21 and the telescoped plug 24 sealing the tube whereby the lever-arm is readily attached to the yoke.

Another feature is the substantial interengagement of the clip with the sheet material afforded by the acute edged and pointed ribs formed on the lug or protuberance 20 plus its general tapered formation in conjunction with the trapezoidal opening 18 the margins of which cooperate with the protuberance 20 and the ribs thereon in gripping the material engaged by the clip.

While a specific embodiment of the invention has been shown and described, the invention is not limited to the exact details of construction set forth, and the invention embraces such changes, modifications and equivalents of the parts and their formation and arrangement as come within the purview of the appended claims.

I claim:

1. In a clasp embodying a yoke the improvement comprising front and back leg members connected by a bow forming the upper end of the clasp when in a vertically disposed position, said front leg member having an aperture, a lever-arm pivoted on said front leg member to swing in part in and out of said aperture, a rearwardly extending protuberance on the upper end of said lever-arm for engaging sheet material to be clasped; said back leg member having an opening formed and arranged to receive said protuberance and the material engaged thereby; said back leg member having side members bordering the ends of said opening the inner margins of which are inwardly and upwardly inclined toward each other, said protuberance having upwardly and inwardly inclined sides spaced from but contiguous to said inner margins formed with a series of transversely extending ledges and ridges terminating at their outer ends in sharp corners for gripping flexible material extended thereover.

2. In a clasp embodying a yoke the improvement comprising spaced front and back leg members connected by a bow, said front leg member having an integral pivot-bar and having a slot and aperture on opposite sides thereof, and a lever-arm having an open ended tube on one end thereof having a side slot adapted to laterally receive said pivot bar to position it within said tube; said tube having margins bordering said side slot one of which margins is inturned relative to the other and a plug insertable lengthwise into said tube into engagement with said inturned margin to close said slot.

3. In a clasp embodying a yoke the improvement comprising front and back leg members connected by a bow, said front leg member having an integral pivot-bar and having a slot and an aperture on opposite sides of said bar, a lever arm having an open ended transverse tube on one end thereof having a side slot adapted to laterally receive said pivot-bar to position it longitudinally within said tube; a cylindrical plug having a diameter slightly exceeding the width of the slot in said tube, said plug being adapted to be impressed into said tube and seated interiorly thereof in gripping engagement with the adjacent margins of said slot.

4. In a clasp embodying front and back leg members resiliently connected together by a spring bow, the improvement comprising a pivot bar on said front leg member, and a lever arm pivotally carried on said pivot bar; a single protuberance on said lever arm having opposed convergent sides consisting of transversely extending parallel stepped ridges having the edges thereof terminating at their ends in acute corners; said back leg member

having an opening adapted to receive said protuberance and having side members with convergent inner margins bordering said opening with which said ridges co-operate to form a grip.
